HYDRAULIC ISOCHRONOUS-DROOP GOVERNOR
 Frederick E. Scheidler, West Hartford, Conn., and Charles F. Stearns, East Longmeadow, Mass., assignors to United Aircraft Corporation, East Hartford, Conn., a corporation of Delaware

Filed May 25, 1964, Ser. No. 369,849

7 Claims. (Cl. 137—35)

This invention relates to governors and particularly to mechanism for changing the functioning of a governor between isochronous and droop or proportional governing.

An object of this invention is mechanism including a droop valve and an integrating valve which will automatically, at a preselected speed, change the governor from a droop or proportional governor to an isochronous governor and establish a hydraulic fluid pressure as the governing output signal.

A further object is mechanism including a droop valve and an integrating valve serially connected to each other which will, at a preselected value or control position, change an isochronous governor into a droop or proportional governor.

A still further object is mechanism for disabling the integrating valve so that the droop valve will produce a hydraulic pressure commensurate with the governor.

These and additional objects and advantages will be apparent from the following specification and accompanying drawings in which:

FIG. 1 is a schematic showing of mechanism incorporating the invention.

FIG. 2 is a graph illustrating the operational characteristics of the mechanism of FIG. 1.

FIG. 3 is a schematic showing mechanism for introducing other variables to the system.

This mechanism has been devised to automatically schedule the change from isochronous governing to droop governing or vice versa and has been shown as incorporated in a fuel control device for purpose of illustration. The device schedules the transition as a function of speed (r.p.m.) and the fuel flow required. Droop and isochronous governors are defined as follows:

Droop governor—a governing device which governs by increases in r.p.m. from a set value, decreasing fuel flow
 Isochronous governor—a governing device which holds a set speed regardless of fuel flow requirements

Now referring to the curves shown in FIG. 2, and tracing the types of governors, first considering the droop type of governor. Assume the governor is set at 82 percent speed at a low condition which would require a steady-state line 0. This condition requires a fuel flow of 48 percent. Now, if the load changes so that the new steady-state operating line is now P, the speed must increase to reduce fuel flow. Since 48 percent fuel flow is too much fuel flow for a new operating line, the engine will increase speed. The droop governor will reduce fuel flow along the droop line until an intersection with the new operating requirements is established. So, from the set value of 82 percent speed, the change in load increased the speed to 85 percent before an equilibrium point was reached.

The isochronous governor, on the other hand, would have accomplished the required change in fuel flow without any change in speed. This ability to hold the constant speed is the chief advantage which an isochronous governor holds over a droop type governor. To make an isochronous governor stable, it must be made to act slowly. The droop governor, on the other hand, is a

more stable and simpler device. The ability of the droop governing device to act rapidly and stably is one of the big advantages that the droop governor has to its credit.

There are jet engine characteristics that make it very desirable to have droop governing during certain speeds particularly at idle and isochronous governing at higher speeds. Again, referring to FIG. 2, the transition device allows isochronous governing at any speed intermediate the transition lines and droop governing at speeds above the top transition line and below the bottom transition line. It will be noted, however, that isochronous and droop governing may occur at the same speed, depending upon the load imposed on the engine or when the engine is undergoing a transition from acceleration to steady-state governing. An example showing the latter condition may be had by referring to the U.S. application Serial No. 337,904, filed on January 15, 1964, and assigned to the same assignee.

Considering in detail the structure chosen to illustrate this invention, the flyballs 10 are rotated about the axis 12 in timed relation with the engine or device, not shown, whose speed is controlled by the fuel of throttle valve 14 positioned by the governor and controlling the flow of fuel to the engine. Centrifugal force acting on the flyballs 10 cause them to rotate about their pivot 13 for positioning the servo pilot valve 16 which, in turn, varies orifice 18 serving to establish a pressure in line 20 which is a function of the actual speed sensed thereby. This is accomplished by metering supply pressure generated by the pumps 22 and flowing through pipe 24. The metered pressure in line 20 is then directed to the droop valve generally indicated by numeral 26 and the integrating valve generally indicated by numeral 28.

Considering for the moment the details of droop valve 26 which comprises a spool member 29 having a pair of lands 30 and 32 and a fluid reaction surface 36. Spring 38 abuts against one end of spool 28 and fluid pressure fed to the opposing end acts on fluid reaction surface 36. A screw adjustment 40 may be incorporated to adjust the height of spring 38 which, in essence, establishes the droop characteristic which will be more fully appreciated from the description to follow.

Integrating valve 28 comprises a spool 42 which is free floating in its cylinder. The maximum displacement of spool 42 is governed by the set screws 44 and 46 which act as stops. This spool carries metering land 48 and a pair of reacting surfaces 50 and 52 located on either end. It will be appreciated that spool 42 serves as an integrator when it is spaced from either of the stops 44 or 46 and it moves when flow is caused to enter or leave chamber 52. That is to say, that spool 42 will translate at a velocity that is proportional to the flow generated by upsetting the pressure balance in the hydraulic circuits connecting to the valve end chambers 51 and 53. This is accomplished by providing orifices 56, 58, 60 and the variable orifices defined by land 32 co-operating with its adjacent port. The areas of orifices 56 and 58 are sized to define a pressure which is equal to one-half the value of the pressure in line 20. The area of orifice 60 is fixed and the area defined by land 32 varies to control the pressure on surface 52. When the relationship of the two areas is such that the pressure intermediate thereof is equal to one-half the pressure upstream of orifice 60, spool 42 will cease movement and become balanced. Since this pressure is identical to the pressure in line 20, its value, therefore, is equal to the value intermediate orifices 56 and 58. Whenever reaction surfaces 50 or 52 sense a differential pressure, it will translate as a function of this difference. Since the velocity of spool 42 is a function of the flow into or out of the end chambers which, in turn, results from a pressure

unbalance, it may be said that this valve integrates the error signal; hence, it is considered an integrating valve.

Next, considering the operation of the droop governor. Flyballs **10** is in reality a speed sensor which positions a servo valve to create a pressure proportional to the speed sensed. This pressure then is fed to orifice **64** disposed in line **66**. A portion of the fluid downstream of orifice **64** is vented to drain through branch line **68**, the speed selector valve **70** and through either of the vent passages **72** or **74** depending on the particular setting of the speed selector valve. The other portion is fed to the underside (reaction surface **36**) of droop valve **26**. It will be appreciated that this pressure downstream of orifice **64** is, in essence, a speed error signal; namely, the value between the pressure created by the speed selector **70** and the pressure created by flyballs **10**.

The desired speed is selected by positioning lever **76** which, in turn, positions rotary valve **70**. Rotary valve sets up a venting area between its cooperating ports to meter fluid to vent passage **72** and/or vent passage **74**. This area controls the pressure drop across orifice **64** and establishes the desired pressure; namely, the pressure that is equivalent to the desired speed of the engine. For a more detailed description of the speed selector device reference is hereby made to patent application entitled "Speed Setting Mechanism and Trimming Means Therefor" recently filed in the Patent Office and assigned to the same assignee. Now, consider the effect that droop valve **26** and integrating valve **28** have upon regulating the throttle valve **14**.

Assume, for the moment, that the speed selected is 82 percent and that the throttle valve is regulating sufficient fuel to run the engine at its equilibrium point on the steady-state line **O**. At this point spool **42** of integrating valve **28** will be in the far left position abutting against stop **44**. Now, consider the case when the load on the engine for some reason has decreased a particular value. This has the tendency of raising the speed of the engine and causing the flyballs **10** to pivot outwardly about pivot point **13**. This causes spool **16** to move to the right for opening the variable orifice **18** which, in turn, increases the pressure in line **20**. This pressure fluid is then fed to droop valve **26**. Fluid reaction surface **36**, feeling the increased pressure, causes spool **28** to shift to the left so that land **30** uncovers its cooperating port. Since land **30** meters to drain, fluid behind metering valve **14** is vented via lines **80, 82, 84, 85** and **87**. Spring **86** acting on the opposite end of throttle valve **14** causes the valve to move upward toward the closed position. Fuel flow then falls off at a rate dictated by spring **38**, as shown by the slope of the droop line. It, therefore, will be appreciated from the above that the droop valve serves to produce droop type governing during this regime of operation.

As noted above, when flyballs **10** move outwardly as a result of an increase in speed being sensed, the pressure in line **20** increased. The fluid reaction surface **50** feels this increased pressure causing spool **42** to remain on stop **44**. Land **32** of droop valve **26** also moved to the left uncovering its cooperating point so as to connect the space adjacent fluid reaction surface **52** to vent via lines **88** and **87**. Hence, the control supplies the proper amount of fuel to hold the engine at its new steady-state operating point defined where droop lines intersect the new load Curve **P**. However, the decrease in fuel flow operates the engine at a new increase in r.p.m., and the integrating valve remained inoperative.

Next, consider the case where the load increases to the new load line designated by Curve **N**. Viewing FIG. 2, it is noted that the isochronous governor will then take over from the transitional line until the fuel is increased to the new point where the isochronous governor line intersects the new steady-state operating line **N** without an increase in speed. As the load increases, the speed tends to reduce so that flyballs **10**, feeling this reduction in

speed, tends to move inwardly rotating about pivot **14**. This serves to position spool **16** to the left for reducing the area of orifice **18** and hence, reducing the pressure in line **20**. Spring **38** of droop valve **26** repositions the droop valve spool **29** to the right since the pressure acting against fluid reaction surface feels a decrease in pressure. This has the immediate reaction of reducing the area defined by metering land **30** to block off the flow, thereby reducing the flow of fluid draining from behind fuel valve **14**. This, in essence, decreases the pressure drop across orifice **90** raising the pressure in line **80** and in the space behind the throttle valve **14** for urging the throttle valve down to the open position for allowing more fuel to enter the engine.

Simultaneously, the pressure difference felt by reaction surfaces **50** and **52** increases in the direction to cause spool **42** to shift to the right. The reason that the pressure difference acting on reaction surfaces **50** and **52** increases is because spool **29**, as mentioned above, had shifted to the right reducing the metering area controlled by land **32**. Since this orifice is in series with orifice **60**, the pressure drop across **60** decreases more than the pressure drop across **56**; hence, the pressure in line **88** increases and the pressure in the space behind reaction **52** likewise increases more than the pressure on reaction **50**. As spool **42** shifts to the right, the metering land **48** reduces the area of its cooperating port. Since this metering area serves to vent pressure from behind throttle valve **14** through lines **80, 82, 84, 90, 92** and **94**, the reduced flow to vent decreases the pressure drop across orifice **90** raising the pressure in line **80** for causing the throttle valve **14** to move toward a more open position for increasing the amount of fuel to the engine. Hence, the droop valve which initially increased the fuel flow to the engine is complimented by the integrating valve which likewise increases fuel to the engine. This has the effect of shifting the droop line vertically along the isochronous governor line so as to change fuel flow without increasing the speed of the engine. When the new steady-state operating condition is met, namely, where the isochronous governor line intersects the steady-state operating line **N**, spool **29** of droop valve **26** will return to its original position and the integrating valve will be at a new position intermediate its stops **44** and **46**. The integrating valve continues to translate until the droop valve is returned to its initial condition which sets the pressure in chamber **53** equal to **51**. In order to achieve this, the speed error pressure in chamber **36** of the droop valve must have returned to its initial value and consequently speed must be equal to its initial value.

When the control is operating at a higher fuel flow at the 82 percent speed value and it intersects the upper transitional line, spool **42** of integrating valve **28** will bear against stop **46** and again the droop valve will take over the control for varying the fuel flow at the new speed condition.

Hence, it will be apparent from the above that during isochronous governing droop valve **26** will always seek an equilibrium position which may be designated at the point where **A'** coincides with point **A**. The isochronous governor during the isochronous governing regime will be at various points intermediate the two stops. When the droop governor takes over control, the integrating valve will be urged against either of the stops and rendered inoperative so that the droop governor completely controls the engine along the various droop lines as indicated by FIG. 2. Of course, the 82 percent speed value was selected merely for illustration purposes but the same governing aspects are attendant regardless of the speed at which the governor is controlling. By virtue of locating the stops of the integrating valve at the proper points, it is possible to have isochronous and droop governing at the higher speeds, and reducing (to some degree) isochronous governing in lower speed regimes.

In the particular embodiment selected to illustrate this invention, the throttle valve **14** is shown as a spring

loaded window type of valve that has a piston head sensing metered servo pressure for positioning the windows for varying fuel flow. A suitable pressure regulator 100 indicated in blank regulates servo supply pressure being fed through line 108 to a constant value and the isochronous-droop governor varies pressure downstream of orifice 90 for positioning throttle valve 14. In certain applications particularly for jet engines, it is desirable to meter fuel as a function of an engine operating parameter such as compressor inlet pressure or compressor discharge pressure or the like as well as speed. In this light the pressure regulator 100 could be replaced by the device shown in FIG. 3.

The mechanism in FIG. 3 serves to create a hydraulic pressure whose value is directly proportional to the pneumatic pressure sensed by bellows 102. Pressure being sensed (either compressor inlet or outlet or the like of a jet-type engine (not shown)) through pipe 104 is admitted internally of the bellows for causing it to expand or compress as a function of the pressure being sensed. The free end of the bellows carries a servo valve 106 which meters supply pressure fed thereto through line 108 (note line 108 is identical to 108 in FIG. 1). The metered pressure in line 110 is admitted to cavity 112 to surround the bellows and on the underside of servo valve 106 via line 114. The forces felt by the internal effective area and the external effective area of the bellows will position the servo valve to an equilibrium point. When equilibrium is reached, the pressure fluid discharging from cavity 112 will be proportional to the pressure internal of the bellows. Of course, the cavity would be made to communicate with line 80 (FIG. 1) and orifice 90 would then be eliminated.

It will be appreciated that the fuel is used as the servo pressure fluid. A separate source of servo fluid may be used without deviating from the scope of this invention.

It should be understood that the invention is not limited to the particular embodiments shown and described herein, but that various changes and modifications may be made without departing from the spirit or scope of this novel concept as defined by the following claims.

We claim:

1. In combination with a speed responsive governor adapted to govern the speed of an engine, a control element controlling the speed of the engine and movable by application of fluid, means for controlling the application of fluid for positioning said control element in accordance with the governor speed so that each particular speed provides a predetermined different element position, means rendered operative at a selected speed to disable said controlling means and control the application of fluid for positioning said control element in various positions independent of any particular governor speed to maintain a constant engine speed.

2. In combination with a speed responsive governor for a turbine type of power plant, a control element controlling the speed of the power plant movable by the application of fluid, means responsive to an off-speed speed of said governor controlling the application of fluid for positioning said control element to maintain a constant speed of said power plant, means disabling said first mentioned means at a preselected element position for taking

over the control of the application of fluid for positioning said element in accordance with the governor speed so that each governor speed has a corresponding element position.

- 5 3. An isochronous-droop governor for a turbine type power plant comprising, in combination, a speed sensing mechanism for developing a hydraulic pressure signal, means responsive to a preselected speed setting for modifying said signal, a droop valve responsive to said modified signal for producing a first hydraulic pressure control signal, a control element responsive to said first hydraulic pressure control signal being positioned in accordance with the speed sensing mechanism so that a particular speed provides a predetermined element position, means including an integrating valve responsive to said hydraulic pressure signal rendered operative at a selected speed providing a second hydraulic pressure control signal to position said control element in various positions independent of said droop valve to maintain a constant power plant speed.
- 10 15 4. An isochronous-droop governor adapted to control the speed of an engine comprising, in combination, a speed sensing mechanism for developing a hydraulic pressure signal in accordance with the speed sensed, a control element, an integrating valve responsive to said pressure signal for positioning said control element to maintain a constant engine speed, means responsive to a preselected speed setting for modifying said hydraulic pressure, a droop valve responsive to said modified hydraulic pressure for disabling said integrating valve for positioning said element in accordance with the speed of the speed sensing mechanism so that each governor speed has a corresponding element position.
- 20 25 30 35 4. An isochronous-droop governor as claimed in claim 4 wherein said disabling means includes an adjustable stop limiting movement of said integrating valve in an element speed reducing direction.
- 30 35 4. An isochronous-droop governor as claimed in claim 4 wherein said disabling means includes an adjustable stop limiting movement of said integrating valve in an element speed increasing direction.
- 40 45 50 4. An isochronous-droop governor as claimed in claim 4 wherein said integrating valve includes a ported casing, a piston slidably mounted in said casing, at least one fluid receiving chamber adjacent one end of said piston, flow passage means directing fluid through the port to said chamber, a first restrictor in said flow passage means upstream of said chamber and a second restrictor in said flow passage means downstream of said chamber, said first restrictor and said second restrictor serving to create a pressure in said chamber at some value proportionally less than said hydraulic pressure signal.
